POWER-DRIVEN CLEANING BRUSH

Arthur Ward, New York, N. Y., assignor to International Paint Company, Inc., New York, N. Y., a corporation of New York

Application July 2, 1948, Serial No. 36,755

6 Claims. (Cl. 15—141)

1

This invention relates to a power driven cleaning brush, and more particularly to a brush for use on ships' bottoms for removing fouling and rust, and under some conditions for removing paint and hard scale.

It has been proposed to employ power driven brushes, particularly for the specific purpose referred to, wherein the brushing elements are either in the form of pivoted striking elements or spring steel wires. Both types of such device have been found unsatisfactory in use because of their failure to last over substantial periods of the rather hard usage to which they are subjected. In the case of resilient fingers, such as spring wires, it has been found that the cleaning elements crystallize and break due to the constant flexing and releasing of the elements. This fault does not occur in those types of brushes which utilize pivoted fingers, but such devices are unsatisfactory because of the rapid wearing of the pivot elements.

An important object of the present invention is to provide a novel power driven brush of the character referred to wherein the cleaning elements employed utilize all of the advantages of the prior structures referred to without their disadvantages, the cleaning elements possessing flexibility in operation without any danger of breakage from crystallization.

A further object is to provide cleaning fingers made up of hard cleaning elements and highly resilient fingers for supporting said elements, the resilient fingers providing the desired degree of flexibility in operation and the rotary action of the brush serving to cause the cleaning elements to remain in their outer circumference of operation by centrifugal force to strike against the surface to be cleaned.

A further object is to provide such a device which may be wholly lacking in any pivotal connection of the cleaning units to the brush and which does not involve the use of any parts subject to crystallization, whereby the device may be subjected to hard usage over substantial periods of time without appreciable wear.

A further object is to provide a novel combination of flexible cleaning units of the character referred to with adjustable regulating plates to predetermine the striking action of the cleaning elements against the surface being cleaned.

Other objects and advantages of the invention will become apparent during the course of the following description.

In the drawing I have shown one embodiment of the invention. In this showing:

Figure 1 is a face view of the device, parts be-

2

ing broken away, and parts being shown in section,

Figure 2 is an enlarged transverse fragmentary sectional view on line 2—2 of Figure 1,

Figure 3 is a side elevation of the device illustrating its operation against a surface being cleaned, the handle being broken away,

Figure 4 is a detail fragmentary sectional view on line 4—4 of Figure 2, and,

Figure 5 is a detail perspective view of one of the cleaning units.

Referring to Figure 1, the numeral 10 designates the cylindrical body of the device having radial extensions 11 at opposite ends provided with edge flanges 12. Over each end of the body 10 and its associated extension 11 is arranged a casing member 13 having edge flanges 14 seating against the flanges 12, as shown at the right hand side of Figure 1, the extensions 11 and members 13 thus forming a housing for a purpose to be described. The casing members 13 are secured in position by suitable screws 15.

The body 10 is provided with a suitable handle 16 through which extend lead wires 17 connected to an electric motor 18 housed within the body 10. An electric motor is preferably employed as the source of power, and any other suitable power source may be employed.

The motor 18 is provided with a shaft 20 extending from one end thereof and journaled in a bearing 21 carried by the body 10. The end of this shaft carries a sprocket 22 around which passes a chain 23, as shown at the right hand side of Figure 1. This chain passes around a sprocket 25 carried by a shaft 26 journaled in bearings 27 formed in the extensions 11. Thus it will be apparent that the shaft 26 is driven by the motor 18, and the sprockets 22 and 25 may be of any relative sizes to drive the brush to be referred to at a desirable speed, for example, approximately 2,000 R. P. M.

The shaft 26 has fixed thereon a pair of spaced discs 30 arranged adjacent the respective bearings 27. These discs support a plurality of transverse parallel rods 31 having their axes equidistantly spaced from the axis of the shaft 26. The rods 31 accordingly will be driven by the discs 30.

A plurality of cleaning units 35 is carried by each rod 31. Each unit comprises a rubber or other elastic finger 36 having its radially inner end looped around the associated rod 31 as at 37 and the end of the finger is riveted to the body thereof as at 38 or fixed thereto in any other suitable manner. To the outer end of each finger or strap 36 is secured a cleaning element 39 in

the form of a section of flat steel spring riveted to the finger 36 as at 40. The fingers 36 associated with each rod 31 are looped around such rod in spaced relation, as shown in detail in Figure 4, and spacing collars 41 are arranged between the loops of the adjacent fingers or straps 36. Each strap is preferably somewhat wider than the space between adjacent pairs of straps, and the fingers of adjacent rods 31 are staggered relative to each other, as will be apparent from an examination of Figure 1. In other words, the fingers 36 and their associated cleaning elements 39 at the top of Figure 1 are offset from the corresponding elements of each next adjacent rod, and accordingly all portions of the surface to be cleaned will be struck by several of the cleaning elements 39 in each rotation of the brush.

Novel adjustment plates act in combination with the cleaning units to hold the brush in proper relation to the work. Each casing member 13 carries a pair of bolts 45 having wing nuts 46, as shown in Figures 1 and 3. These bolts extend through slots 47 formed in distance plates 48, the operative edge 49 of which is curved in an arc of a circle which is concentric with the axis of the shaft 26 in the usual preferred adjustment of the plates 48. The working edges 49 are engageable with the surface 50 of the work, as indicated in Figures 2 and 3.

OPERATION

When it is desired to subject a surface such as a ship's bottom to a cleaning action, the plates 48 will be adjusted to positions in which the working edges 49 thereof are arranged radially inwardly a reasonable distance from the circles defined by the radially outer edges of the cleaning elements 39, for example, in the approximate positions shown in Figures 2 and 3. The motor 18 is started in operation, whereupon the operator, supporting the device by the handle 16, will move the device in proximity to the surface 50 of the work until the working edges 49 of the plates 48 engage the surface of the work. As stated, the edges 49 will lie radially inwardly of the circles defined by the radially outer edges of the cleaning elements 39, and as the shaft 26 is rotated, the cleaning elements 39 strike smartly against the surface 50 to clean any rust or fouling therefrom.

After the initial striking of each element 39 against the surface 50, such element will move along the surface 50 and its distance from the axis of the shaft 26 will decrease. This relative radially inward movement of the cleaning elements 39 is compensated for by the flexing of the fingers or straps 36. In practice, these straps are formed of soft rubber, but they may be made of any suitable material, such as leather, so long as they possess a substantial degree of flexibility, without crystallizing. The rotational speed of the shaft 26 causes the cleaning elements 39 to be maintained by centrifugal force in their normal rotational paths of movement and the plates 48 hold the brush in proper relation to the work to permit the cleaning elements 39 to perform the most efficient cleaning action.

In this connection it is noted that in the absence of the plates 48, a workman would be called upon to use a substantial degree of judgment as well as a reasonable degree of strength to hold the device in the proper cleaning position. Without the plates 48, the operator in most instances will move the device too close to the work, in

which case the elements 39 would strike the work surface at a much higher point and accordingly at a substantially greater angle, in which case the efficiency of the cleaning action would be greatly reduced. The plates 48 hold the device in fixed relation to the work without the exercise of physical strength and judgment on the part of the operator so that the cleaning elements strike a glancing blow against the surface to be cleaned at an acute angle relative thereto. In Figure 2, it will be noted that the cleaning element at the right side of the figure and above the point at which the plate 48 contacts the work is just about to strike the work a glancing blow at an acute angle. The plates 48 readily may be adjusted by loosening the wing nuts 46 so that the cleaning elements 39 strike the surface at the most effective angle for cleaning.

There are no pivots associated with the cleaning units at which point excessive wear can occur, and there are no hard resilient elements, such as spring fingers, tending to hold the cleaning elements 39 in their proper operative positions relative to the work. If rubber fingers 36 are used, these fingers will be resilient but they are soft and not hard, as is true of spring steel, the use of which has been found so highly impracticable. These fingers are completely free to flex upon the striking of each cleaning element against the surface, without any injury whatever thereto, and the present device has been found to last for substantial periods in the hard usage to which it is subjected.

While the device is primarily intended for cleaning rust and fouling from ships' bottoms, it obviously may be used for cleaning other surfaces where a sharp hard striking force is required. Attention is also invited to the fact that while relatively thin light cleaning elements 39 are employed in the primary use of the device for removing loose rust, fouling matter, paint blisters, etc., from ships' bottoms, substantially heavier cleaning elements 39 may be used where it is desired to remove solid paint and hard scale. With the use of light cleaning elements 39, a highly effective cleaning action is provided but the device will not remove tightly adhering solid paint.

I claim:

1. A rotary brush for cleaning ships' bottoms and the like comprising a rotary unit having shaft means for rotatably mounting same, spaced supporting members carried by said rotary unit and having their axes equidistantly spaced from the axis of rotation of said shaft means, and a plurality of cleaning units carried by each supporting member, each cleaning unit comprising a hard surface-engaging element spaced outwardly of the associated supporting member wholly independent of adjacent elements, and a flexible element connecting such surface-engaging element to the associated supporting member, said surface-engaging and flexible elements being relatively narrow measured in a direction lengthwise of said supporting members, said flexible elements being formed of strips of soft flexible elastic material and having a flexibility such that they are readily bendable under the influence of radially inwardly applied forces, whereby such surface-engaging elements are caused to follow normal rotational paths of movement by centrifugal force and are readily deflectable radially inwardly of such paths upon striking a surface to be cleaned.
2. A rotary brush for cleaning ships' bottoms

and the like comprising shaft means, spaced collars carried by said shaft means, a plurality of spaced parallel rods secured at their ends to said collars and circumferentially arranged around said shaft means, and a plurality of cleaning units carried by each rod, each cleaning unit comprising a hard surface-engaging element spaced outwardly of the associated rod wholly independent of adjacent elements, and a flexible element connecting such surface-engaging element to the associated rod, said surface-engaging and flexible elements being relatively narrow measured in a direction lengthwise of said rods, said flexible elements being formed of strips of soft flexible elastic material and having a flexibility such that they are readily bendable under the influence of radially inwardly applied forces, whereby such surface-engaging elements are caused to follow normal rotational paths of movement by centrifugal force and are readily deflectable radially inwardly of such paths upon striking a surface to be cleaned.

3. A rotary brush of the type set forth in claim 2 wherein each of said flexible elements has its inner end looped around the associated rod to provide overlapping portions secured to each other adjacent the associated rod.

4. A rotary brush for cleaning ships' bottoms and the like comprising a rotary unit, and a plurality of cleaning units carried by said rotary unit, each cleaning unit comprising a short section of hard material spaced radially outwardly of said rotary unit and forming a surface engaging element wholly independent of adjacent elements, and a relatively narrow and thin strip of soft flexible material secured respectively at its radially outer and inner ends to said surface-engaging element and to said rotary unit, said strips having a flexibility such that they are readily bendable under the influence of radially inwardly applied forces, whereby such surface-engaging elements are caused to follow normal rotational paths of movement by centrifugal force and are readily deflectable radially inwardly of such paths upon striking a surface to be cleaned, said cleaning units being arranged in sets extending generally longitudinally of said rotary unit with the cleaning units of each set spaced from each other, the cleaning units of each set being staggered longitudinally of said rotary unit relative to the cleaning units of the adjacent sets with the width of each surface-engaging element at least equal to the space between adjacent pairs of such elements whereby, in the rotation of said cleaning units about the axis of said rotary unit, all portions of the surface being cleaned will be engaged by said surface-engaging elements within the limits of the outermost of such elements.

5. A rotary brush for cleaning ships' bottoms

and the like comprising shaft means, means for rotatably supporting said shaft means, a plurality of independent cleaning units extending radially outwardly from the axis of rotation of said shaft means, said cleaning units comprising hard surface-engaging elements and relatively narrow soft flexible strips connected at their outer ends to said surface-engaging elements and having their inner ends fixed relative to said shaft means, said strips being formed of a relatively narrow and thin flexible extensible material and having a flexibility such that they are readily bendable under the influence of radially inwardly applied forces, whereby said surface-engaging elements are caused to follow normal rotational paths of movement by centrifugal force and are readily deflectable radially inwardly of such paths upon striking a surface to be cleaned, and stationary gauge elements carried by the means for rotatably supporting the shaft means, said stationary gauge elements having edges spaced radially from the axis of said shaft means and curved concentric with said axis for engagement with the surface of the work to predetermine the engagement of said surface-engaging elements with such surface.

6. A rotary brush of the type set forth in claim 5 including stationary means adjustably securing said gauge elements to determine the distance between said surface-engaging edges and the axis of rotation of such shaft means.

ARTHUR WARD.
